UNITED STATES PATENT OFFICE

ROBERT J. HUTT AND GEORGE A. HUTT, OF BROOKLYN, NEW YORK

DESIGN FOR A DOILY

Application filed August 31, 1932. Serial No. 44,732. Term of patent 3½ years.

To all whom it may concern:

Be it known that we, ROBERT J. HUTT and GEORGE A. HUTT, residing at Brooklyn, in the county of Kings and State of New York, have invented a new, original, and ornamental Design for Doilies, of which the following is a specification, reference being had to the accompanying drawing, forming part thereof.

The figure is a plan view of a doily, showing our design in general outline and substantially one-fourth thereof in detail, except for the center wreath which is shown complete; the design illustrated in detail is repeated continuously in the other three-fourths of the doily, to complete the design.

We claim:

The ornamental design for a doily, as shown and described.

ROBERT J. HUTT.
GEORGE A. HUTT.
